ATTORNEY.

UNITED STATES PATENT OFFICE.

JOHN W. ANDERSON AND JOHN T. GAY, OF KENDALL, WISCONSIN.

CAR-COUPING.

SPECIFICATION forming part of Letters Patent No. 247,471, dated September 27, 1881.

Application filed February 19, 1881. (Model.)

To all whom it may concern:

Be it known that we, JOHN W. ANDERSON and JOHN T. GAY, of Kendall, in the county of Monroe and State of Wisconsin, have invented certain new and useful Improvements in Car-Couplings; and we do hereby declare that the following is a full, clear, and exact description of the invention, that will enable others skilled in the art to which it appertains to make and use the same, reference being had to the accompanying drawings, and to the letters or figures of reference marked thereon, which form a part of this specification.

The same letters and figures of reference are used to indicate the corresponding parts.

After describing the invention, its nature and extent will be shown in the claims.

Figure 1 is a vertical longitudinal sectional view of our invention, showing all the parts in their proper position. Fig. 2 is the same view, not showing the link in place. Fig. 3 is a horizontal sectional view, looking down upon the parts of our invention.

A is the draw-bar head. B is the pin. C is the block, which is concave in front to receive the link *a*, which connects the two cars. D is the spindle, which is attached to the rear of the block C. E and E' are springs which surround the spindle, the spring E being placed between the block C and the cross-bar G, and the spring E' being placed in the rear of the collar F. The bolts H and H' pass through slots in the draw-bar head, and are made to screw into the cross-bar G, and thus hold it rigidly in position. The collar F is rigidly fastened to the spindle D. The opening in the draw-bar head terminates in a circular cavity, which receives the rear end of the spindle and the spring E'.

The springs E E' may both be used at the same time, or the rear spring may be used alone.

When the screw-bolts H H' are screwed into the cross-bar G, and thus it is held firmly in position, then both springs are used; but when the screw-bolts H H' are not used, then only the rear spring is used.

When the rear spring only is used and becomes unserviceable, then the front spring may be used.

When in use, the pin is raised to the top of the block C, on which the pin rests. The link presses against the block C, when the pin drops, and thus the cars are connected.

Having now described our invention, what we claim, and desire to secure by Letters Patent, is—

1. The draw-bar head A, the pin B, and the block C, in combination with the spindle D, the spring E, the cross-bar G, and the screw-bolts H and H', substantially as shown and described, and for the purposes set forth.

2. The block C, the spindle D, the spring E, and the cross-bar G, in combination with the collar F, the spring E', the pin B, the draw-bar head A, and link *a*, substantially as shown and described, and for the purposes set forth.

In testimony that we claim the foregoing we have hereunto set our hands this 10th day of January, 1881.

JOHN W. ANDERSON.
JOHN T. GAY.
